FUNNEL WITH SPOUT AND VENT CLOSURE

Gilbert H. Morrison, Peotone, Ill.

Application December 15, 1950, Serial No. 200,985

2 Claims. (Cl. 226—34)

1

This invention relates to improvements in funnels, and more particularly to an improved funnel provided with valve means to prevent overflow of liquid from a vessel being filled by the use of the funnel.

A main object of the invention is to provide a novel and improved safety funnel device which is simple in construction, which is easy to use, and which prevents waste of liquid by preventing liquid from overflowing from the top of a vessel being filled by the use of the funnel.

A further object of the invention is to provide an improved safety funnel device which is inexpensive to manufacture, which involves only a few parts, which is sturdy in construction, which greatly reduces hazards in filling vessels with inflammable liquids, such as gasoline and the like, and which provides a great saving in time in filling vessels, as well as being adaptable for use on vessels having different sizes of filling openings.

Further objects and advantages of the invention will become apparent from the following description and claims and from the accompanying drawings, wherein:

Figure 1 is a top plan view of an improved funnel device constructed in accordance with the present invention.

Figure 2 is a vertical cross sectional view taken on the line 2—2 of Figure 1.

Figure 3 is an enlarged cross sectional detail view taken on line 3—3 of Figure 2.

Figure 4 is an enlarged cross sectional detail view taken on line 4—4 of Figure 2.

Figure 5 is an enlarged cross sectional detail view taken on line 5—5 of Figure 2.

Figure 6 is a cross sectional detail view taken on line 6—6 of Figure 5.

Figure 7 is an enlarged fragmentary detail view showing the pivoted locking arm of the funnel device in valve-locking position subsequent to the elevation of the valve rod of the device.

Referring to the drawings, the improved funnel device is designated generally at 11 and comprises a hollow body having the downwardly tapering conical main portion 12, the cylindrical top rim 13 and the depending vertical discharge spout 14 at the lower end of the conical portion 12. Designated at 15 is a transversely extending support bar which is of inverted V-shape in cross section, as shown in Figure 3, and which extends diametrically across the rim 13. The bar 15 is formed at its ends with the securing flanges 16, 16 through which extend the fastening bolts 17, 17 which fasten the flanges 16, 16 to the rim 13.

Designated at 18 is a second bar member which is of inverted V-shape in cross section and which is secured in the conical portion 12 and which extends in a direction transverse to the direction of the bar member 15. The bar member 18 extends diametrically across the conical funnel portion 12. Designated at 19 is a vertical rod extending slidably through central apertures formed respectively in the bar members 15 and 18, said rod being formed at its top end with a horizontal handle portion 20. Designated at 21 is a valve disc carried at the lower end of the rod 19, said valve disc being slidable on the rod 19 and being urged upwardly against a cotter pin 22 by a coil spring 23 encircling the lower end portion of the rod 19 and bearing between the valve disc 21 and a nut 24 threaded on the rod 19. Designated at 25 is an arm pivoted at 26 to the rod 19, said arm 25 being of generally inverted V-shape in cross section and being located immediately above the bar member 15. The arm 25 is formed with a finger 26' extending at right angles to the main portion of the arm. The free end of arm 25 is formed with a V notch 27 adapted to straddle the bar member 15 when the rod 19 is elevated, as shown in Figure 7, thereby locking the rod 19 in elevated position. In this position, the valve 21 is forced into sealing contact with the bottom rim of the discharge spout 14 against the pressure of the coil spring 23. Since the arm 25 is freely hinged to the rods 19 and 26, said arm 25 falls by gravity into the position of Figure 7 when the rod 19 is elevated, thereby automatically locking the valve disc 21 in sealing position. In order to return the valve disc 21 downwardly to open position, it is necessary to rotate the arm 25 counter-clockwise, as viewed in Figure 7, by means of the finger grip portion 26' of the locking arm 25.

Designated at 28 is a screen which is provided at the lower end of the conical portion 12, the rod 19 extending slidably through the center of the screen 28.

Designated at 29 is a vent tube which is secured inside the body of the funnel device in any suitable manner and which is provided at its top end with the open curved portion 30 and at its bottom end with the vertical open portion 31. Designated at 32 is a rod member having a vertically extending plug portion 33 aligned with the tube portion 31 and having the eye portion 34 encircling the lower end of the rod 19 and clamped thereto by a nut 35. From Figures 2 and 5 it will be apparent that when the rod 19 is elevated, the plug portion 33 enters the vent

tube portion 31 and seals said vent tube portion. Therefore, liquid will flow freely through the funnel device when the rod 19 is in the position shown in Figures 2 and 5 but flow of liquid will be cut off when the rod 19 is elevated and locked because of the combined sealing action of disc 21 on the lower rim of the discharge spout 14 and the closing of the vent tube 29 by the entry of the sealing plug 33 into the lower tube portion 31.

Secured to the lower portion of the conical funnel element 12 are a plurality of annular sealing gaskets shown respectively at 36 and 37, said gaskets being of decreasing size in order to engage with the filling openings of vessels of correspondingly decreasing size. For example, Figure 4 illustrates the engagement of the sealing gasket 37 with the rim 38 of a vessel having a relatively small filling opening. Designated at 40 is an annular ring member provided with a pair of diametrically opposed locking lugs 41, 41 adapted to enter notches in the rim of a relatively large filling opening. When the funnel device is rotated said device will be locked to the filling opening with the gasket 36 in sealing relation to the rim of the opening. Similarly, the lower portion of the member 40 has secured thereto the diametrically opposed locking lugs 43, 43 adapted to enter notches 44, 44 in the rim 38 and to lock the funnel device to the filling opening responsive to rotation of the device to the dotted line positions of lugs 43, 43 shown in Figure 4, whereby the gasket 37 will be in sealing relation to rim 38.

It will be apparent that in using the device, said device is first secured to the filling opening of a vessel in sealing relation to the rim of the filling opening of the vessel, in the manner above described, and then the liquid to be poured into the vessel is admitted into the top portion of the device. The liquid will flow into the vessel until the vessel is filled, whereupon liquid will rise in the funnel device. When this is observed, admission of liquid is discontinued and the operator elevates the rod 19 by means of the handle 20, causing the locking arm 25 to drop into locking position, shown in Figure 7. The surplus liquid is then trapped in the funnel device. The funnel device may then be disengaged from the rim of the filling opening of the vessel and the surplus liquid trapped therein may be poured back into the supply reservoir or vessel or into any other suitable container. This prevents waste of the liquid and also eliminates the hazards of inflammable or explosive liquids such as gasoline or the like from overflowing or spilling around the receptacle being filled. In the case of gasoline or similar inflammable liquid, the overflow of liquid constitutes a dangerous hazard, and the present invention substantially eliminates such hazard by preventing overflow.

While a specific embodiment of an improved funnel device has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

10. 1. A funnel of the character described comprising a downwardly tapering hollow body having a bottom discharge opening, a rod, guide means slidably supporting said rod in axial position in said body, a valve member secured to the lower end of said rod and being sealingly engageable with said opening responsive to elevation of the rod, a locking arm pivoted to said rod above the guide means and being lockingly engageable with said guide means responsive to the elevation of the rod to sealing position, a vent tube secured in said body, and a plug member secured to said rod and arranged to sealingly engage said vent tube responsive to elevation of the rod.
15. 2. A funnel of the character described comprising a downwardly tapering hollow body having a bottom discharge opening, a rod, guide means slidably supporting said rod in axial position in said body, a valve member secured to the lower end of said rod and being sealingly engageable with said opening responsive to elevation of the rod, a locking arm pivoted to said rod above the guide means and being lockingly engageable with said guide means responsive to the elevation of the rod to sealing position, a vent tube secured in said body, and a plug member secured to said rod and arranged to sealingly engage said vent tube responsive to elevation of the rod.
20. 3. A funnel of the character described comprising a downwardly tapering hollow body having a bottom discharge opening, a rod, guide means slidably supporting said rod in axial position in said body, a valve member secured to the lower end of said rod and being sealingly engageable with said opening responsive to elevation of the rod, a locking arm pivoted to said rod above the guide means and being lockingly engageable with said guide means responsive to the elevation of the rod to sealing position, a vent tube secured in said body, and a plug member secured to said rod and having an upstanding sealing element arranged to sealingly engage in said vent tube responsive to elevation of the rod, a plurality of spaced annular sealing gaskets secured to the lower portion of said body and extending outwardly therefrom, said gaskets being vertically spaced and decreasing in diameter toward the lower end of the body, and a plurality of locking lugs secured to said body below each of the sealing gaskets and extending radially outwardly from the body.
